UNITED STATES PATENT OFFICE.

NICHOLAS SCHRODER, OF NEW YORK, N. Y.

PASTING-MACHINE.

No. 879,329.

Specification of Letters Patent.

Patented Feb. 18, 1908.

Application filed May 28, 1907. Serial No. 376,119.

To all whom it may concern:

Be it known that I, NICHOLAS SCHRODER, a citizen of the United States, residing in the city of New York, borough of Brooklyn, in the county of Kings and State of New York, have invented a certain new and useful Improvement in Pasting - Machines, of which the following is a specification.

The invention relates to machines for applying an adhesive to sheets of paper and analogous material and attaching such sheets to various articles, and more particularly to machines for affixing flies to the interior of paper boxes.

15 The object of the invention is to provide a machine by which the operations of applying the paste and attaching the flies to the inner margins of the boxes may be economically and accurately performed and which shall be 20 simple in construction and easily operated.

The invention consists in certain novel features and details of construction by which the above objects are attained, to be hereinafter described.

25 The accompanying drawings form a part of this specification and show a preferred form of the invention.

Figure 1 is a front view of the machine. Fig. 2 is a side view, and Fig. 3 is a plan view 30 of certain portions, partly in horizontal section. Figs. 4 and 5 are vertical sections on a larger scale, showing the paste-trough and adjacent parts in several positions assumed in the pasting and attaching operations. Fig. 6 is a longitudinal vertical section showing a portion of the paste-trough on a still larger scale, and Fig. 7 is a corresponding transverse section.

Similar letters of reference indicate the 40 same parts in all the figures.

A is the frame of the machine, comprising four upright posts joined by horizontal braces and inclosing a fixed table B at a height convenient for the operator. On the 45 table B is a bed C arranged to slide in guides B¹ extending from front to rear and carries the pack of superposed flies M at the front. The pack is loosely inclosed between a fixed ledge B² at one end, an adjustable gage C¹ at 50 the opposite end, and a similar gage C² at the rear; the front of the pack lies about flush with the front edge of the bed and is confined at this edge by the upturned ends or fingers C³ of flat springs C⁴ attached to the 55 under face of the bed.

Lying loosely on the upper surface of the

pack is a weight comprising a bar D supported on curled strips of metal D¹ extended rearwardly in the form of arms D² having holes d in which are engaged pins c on the upper edge of the rear gage C², as shown, so that the weight may be adjusted forward or backward as required for wider or narrower flies or to vary the point at which its light force shall be applied. The under faces of the curled strips are smoothly finished to 60 permit the topmost fly to be easily withdrawn beneath them.

E is the paste-trough, preferably of triangular cross-section, arranged to slide vertically in ways A² on the front posts of the frame. It is open at the top to receive paste and the bottom is formed of a strip of sheet metal E¹ semicircular in cross-section, with a line of small perforations e along the center line of its lower convex face through which paste from the interior of the trough is delivered to the upper face of the topmost fly of the pack. On the oblique rear face of the trough is a strip or follower E² projecting 70 downwardly beyond the bottom of the trough and closely adjacent thereto. It is arranged to slide vertically by rods E³ attached thereto and passing through eyes or loops E⁴ on the trough. The upper ends of the rods E³ are screw-threaded and loosely engaged with levers E⁵ extending across the open top of the trough and fulcrumed at e¹ on the top edge of the front board thereof. Nuts E⁶ on the rods above and below the 75 levers adjustably connect these parts and the weight of the follower is sufficient to hold it in the lowered position until it rests upon the pack when the trough is lowered. Suspended from the levers E⁵ is a round bar E⁷ lying in the concave trough-bottom and serving to open or close the perforations e according as the follower and levers are raised or lowered relatively to the trough. Forward 80 of the trough and sliding in ways A³ on the same posts and parallel with the ways A², is a presser F in the form of a flat board or plate having a plane lower edge and serving to press the box downward against the pasted upper fly of the pack.

In the machine as illustrated the several 85 motions are produced by foot-levers G and H through cords extending therefrom over guide-sheaves and pulleys to the bed, trough, and presser which are returned by 90 the action of weights similarly connected. It will be understood that springs may be 95 100 105 110

employed instead of the weights, and the motions may be induced by cams or other mechanism acting on the foot-levers or their equivalents.

- 5 The paste-trough is held in the elevated position by the gravity of weights I I attached to cords I¹ I¹ running over pulleys I² I² on the top of the frame and fastened to the trough at its ends, and is depressed by 10 the foot-lever H through cords I³ I³ running therefrom over guide-sheaves I⁴ I⁴ and I⁵ I⁵ and secured to the trough at I⁶ I⁶.

Weights J J on the cords J¹ J¹ from the presser F, running over pulleys J² J² similarly elevate this portion of the mechanism which is depressed by the foot-lever G through cords J³ J³ running on guide-sheaves J⁴ J⁴ and J⁵ J⁵ and attached to the presser at J⁶ J⁶.

- 20 Attached to the under face of the bed C near the front is a cord K¹ running over a pulley K² on the frame at the rear and carrying a weight K serving to draw the bed with its pack of flies and attachments toward the 25 rear; the forward movement is induced by the descent of the foot-lever G through the medium of a cord K³ running over a pulley K⁴ at the front and fastened to the bed C near the rear. The cords K¹ K³ lie in a narrow 30 space b provided in the table B, and the latter is also grooved as at b¹ b¹ to permit the depression of the spring-fingers C³ C³.

The operation of the machine is as follows:—Assuming the trough to be supplied 35 with paste, and, with the presser F, to be in the elevated position, and the bed C retracted and carrying a pack of flies so placed that the forward edge of the pack lies close to the fingers C³, it will be seen by referring 40 to Fig. 4 that the margin of the top-most fly M is directly below the line of perforations in the bottom of the trough; by depressing the foot-lever H the trough is lowered to apply the paste, but before such contact the follower E² strikes the fly and through 45 its rods E³ and the levers E⁵ holds the bar E⁷ against further descent and thus releases the paste which is then delivered by the continued downward movement of the trough, 50 as indicated in the dotted lines in the figure. The foot-lever is now released and the trough begins to rise while the follower by gravity holds down the pasted fly until adherence of the latter to the trough is broken and the 55 trough rises sufficiently to close the perforations by the bar E⁷, when it also is lifted with the trough to the fully elevated position clear of the pack and the weight D thereon. The foot-lever G is then depressed, forcing 60 the bed C forward, the operator at this time applies the open face of a box N to the bed with the inner surface of its side-wall above the pasted margin of the fly and resting lightly upon the ends of the spring-fingers C³. 65 The further descent of the foot-lever G brings

the presser F down on the exterior of the box and forces it down in opposition to the force of the spring-fingers into close contact with the pasted margin of the fly, as shown in Fig. 5, spreading the paste by pressure and insuring complete union. The release of the foot-lever G allows the presser to rise and the bed C to recede and the spring-fingers lift the box with its attached fly adhering thereto, thus separating the fly from the pack, and it is 75 finally drawn from beneath the weight D by the withdrawal of the box, the spring-fingers preventing the succeeding fly or flies from following it.

The paste-trough is of sufficient length to 80 operate on the longest flies, but as the latter vary in length to conform to the length of boxes, it is necessary to reduce the effective length of the pasting line accordingly so that the machine may be adapted to serve on all 85 sizes. This is accomplished by a thin slide or gate L curved to match to the inner concave face of the trough-bottom, introduced at one end thereof and covering the holes e; by inserting it the proper distance the desired 90 length of pasting line is obtained, and, by reason of the thin metal used in its construction, it does not interfere with the closing action of the bar E⁷ upon the remaining un-covered perforations.

On the front edge of the bed C is a series 95 of notches c¹ each adapted to receive one end-wall of a box to be treated, the other end-wall lying closely adjacent to the side of the bed, thus permitting boxes of different 100 lengths to be operated upon with flies of corresponding lengths.

The connections between the bar E⁷ and levers E⁵ are adjustable, and with the similarly connected rods E³ from the follower E² 105 permit these parts to be conditioned to control the flow of paste and the action of the follower on the fly, and the adjustable gages C¹ C² permit packs of various lengths and widths to be properly presented.

It will be observed that the machine is of 110 few parts, simply constructed and easily operated.

The cords confer an elasticity or yielding quality to the pressure of the paste-supplying and pressing operations which is of advantage in a machine of this character, and permit the pasting to be properly effected irrespective of the thickness of the fly-pack, thus obviating the necessity of compensating 115 mechanism for this purpose, but the several movements may be produced by other and more positive means, and the mechanism adapted for other purposes than fly pasting.

I claim:—

1. In a machine of the character set forth, a horizontally movable bed carrying a number of superposed sheets, a paste-trough above said sheets arranged to deliver paste through the bottom thereof, and means for lowering 130

- said trough into contact with the uppermost of said sheets.
2. In a machine of the character set forth, a slidable bed carrying a number of superposed sheets, a paste-trough above said sheets arranged to deliver paste through the bottom thereof, means for lowering said trough into contact with the uppermost of said sheets, means for pressing a box upon 10 said pasted sheet and means for moving said bed and sheets from the pasting position into operative relation to said pressing means.
3. In a machine of the character set forth, a bed arranged to slide and carrying a number of superposed sheets, a paste-trough above said sheets, a presser adjacent to said trough, means for lowering said trough to supply paste to the uppermost of said sheets and again raising it, means for moving said 20 bed and its sheets into position beneath said presser, and means for lowering said presser upon a box applied upon said pasted sheet.
4. In a machine of the character set forth, a bed carrying a number of superposed sheets, a paste-trough above said sheets, means for lowering said trough into contact with the uppermost of said sheets and again raising it, a follower arranged to press upon 25 said sheets and maintain its pressure after 30 said trough has begun its upward movement.
5. In a machine of the character set forth, a bed carrying a number of superposed sheets, a paste-trough above said sheets, 35 means for lowering said trough into contact with the uppermost of said sheets and again raising it, a follower carried by said trough and arranged to press upon said sheets and maintain its pressure after said trough has 40 begun its upward movement.
6. In a machine of the character set forth, a bed, a paste-trough above said bed, a perforated bottom in said trough, and a bar within said trough arranged to rise and sink 45 relatively thereto and open and close such perforations.
7. In a machine of the character set forth, a bed, a paste-trough arranged to reciprocate vertically above said bed, a perforated bottom in said trough, a follower carried by said trough and movable relatively thereto and projecting below said bottom, a bar within

said trough, and connections from said follower to said bar whereby the rising and sinking movements of said follower relatively to said trough causes said bar to rise and sink and close such perforations.

8. In a machine of the character set forth, a paste-trough, a bottom therefor having a line of perforations therein, and a gate arranged to be moved longitudinally of said bottom to cover or uncover such perforations and adjustably control the length of the pasting line.

9. In a machine of the character set forth, a bed carrying a number of superposed sheets, compressible spring fingers against which the front edges of said sheets are received, and a presser arranged to force a box upon the topmost of said sheets and depress 70 said fingers, the latter also serving to lift said box and an attached sheet when said presser is removed.

10. In a machine of the character set forth, a bed carrying a number of superposed sheets, and a series of notches in the edge of said bed, each notch arranged to receive an end wall of a box of different size applied upon the uppermost of said sheets.

11. In a machine of the character set forth, a bed, a vertically slidable paste-trough, a vertically slidable presser adjacent to said trough, foot-levers and connections therefrom for lowering said trough and presser, and weights and connections therefrom for raising said trough and presser.

12. In a machine of the character set forth, a horizontally slidable bed, a vertically slidable paste-trough, a vertically slidable presser adjacent to said trough, a foot-lever and cords therefrom to said trough for lowering the latter, a foot-lever and cords therefrom to said bed and to said presser for moving said bed and presser, and means for inducing the return movements of said trough, bed, and presser.

In testimony that I claim the invention above set forth I affix my signature, in presence of two witnesses.

NICHOLAS SCHRODER.
